UNITED STATES PATENT OFFICE.

CARL E. CAPMAN, OF CHICAGO, ILLINOIS, ASSIGNOR TO JOSEPH SALTZMAN, OF CHICAGO, ILLINOIS.

GARMENT-PRESSING MACHINE.

1,316,559.

Specification of Letters Patent. Patented Sept. 23, 1919.

Application filed June 7, 1917. Serial No. 173,270.

To all whom it may concern:

Be it known that I, CARL E. CAPMAN, a citizen of the United States, residing at Chicago, in the county of Cook and State of Illinois, have invented certain new and useful Improvements in Garment-Pressing Machines, of which the following is a specification.

This invention relates to improvements in garment pressing machines, and it has for its salient object to provide a simplified and improved machine, such improvements comprising an improved form of supporting frame and overhead trolley mechanism; an improved pressing iron suspension mechanism; improvements in the details of construction whereby said suspension mechanism is made adjustable as to length and as to weight-counterbalancing effect; improvements in the means for detachably connecting pressing irons of various sizes to said suspension mechanism; improvements in the mounting of the overhead trolley track, whereby greater freedom of movement is insured; and in general, to provide an improved mechanism of the character referred to.

To the above ends the invention consists in the matters hereinafter described, and more particularly set forth in the appended claims.

In the drawing—

Figure 1 is a perspective view showing the machine as viewed from the front; Fig. 2 is a sectional detail of the adjustable parts of the iron-suspending mechanism;

Fig. 3 is a perspective view of an adjustable clamp forming the means of attaching the iron to the suspending devices;

Fig. 4 is a sectional detail showing the connection between one end of the track-bar and the suspension link.

Referring to the drawings, 1 designates as a whole a pressing-table, which may be of any suitable construction provided it is rigid and strong so as to afford ample support for the pressing machine proper which is mounted thereon. 2 designates a standard or upright, which is conveniently made of tubing and is rigidly secured to the table top, conveniently by means of a base casting 3 having outstanding arms 4 resting upon and bolted to said top. The upper end of the standard is provided with rigid

angle fittings 5 in which are secured supporting bars 6, 6', arranged to extend approximately at right angles to each other and in the same horizontal plane. At their outer ends the arms 6, 6', carry depending hanger rods 7, 7'; which are conveniently fixed to the supporting arms by being inserted and secured in suitable apertures in the latter. The hanger rods are parallel with each other, and serve to support a trolley bar or track 8, which latter is apertured at each end to fit loosely upon the respective hangers 7, 7'.

Coiled expansion springs 9 are mounted on the lower ends of the respective hanger rods, interposed between washers 10 keyed upon the extremities of the rods and the under side of the trolley bar, so that the latter is yieldingly supported as to each of its ends. The springs 9 are so formed as to normally expand, and of such strength or stiffness that they will support a part only of the weight of the pressing iron. A confining spring 11 is mounted upon one of the hanger rods 7 between the upper side of the trolley bar 8 and the suspension arm 6; the purpose of this confining spring being to prevent the trolley bar from rising too high at that end and getting into a binding or locking position in operation of the machine.

12 designates as a whole a trolley carriage and its supporting wheel. Connected with the carriage is a depending rod 13, carrying at its extreme lower end a guide-block 14 through which is arranged to extend and slide a suspension rod 15. An adjustable stop-block 16 is mounted to embrace both rods 13 and 15, and a thumb-nut 17 threaded into the stop-block 16 serves to lock the latter in adjusted position upon rod 15 while permitting it to slide freely upon rod 13. The upper end of rod 15 is headed to prevent it from accidentally slipping through the block 16 when the thumb-nut is released.

Upon the rod 15 between blocks 14 and 16 is mounted a coiled expansion spring 18, which is of such strength or stiffness as to only partly support the weight of 105 the iron.

With the lower end of the rod 15 is pivotally connected a curved or bail-shaped link 19, which carries at its lower end an adjustable clamp 20 (see Fig. 3) which is 110

adapted to be rigidly clamped upon the upper side of the body of the pressing iron 21. The lower end of the bail 19 is notched in its upper side and is slipped through a 5 staple 20' upon the clamp and interengaged with the latter by the notch. This permits practically a universal movement of the iron relatively to the bail. The clamp 20 comprises a body bar 22 and adjustable jaws 10 23, 23', connected with the body by slot-and-screw connections; the arrangement being such that the clamp can be securely fixed upon the body of the iron while maintaining the staple 20' coincident with the center of 15 gravity of the iron.

The union 5' which carries the fittings 5 is threaded upon the standard and held at any angular adjustment desired. By providing a double width table or simply setting another table back of the first the pressing machine may be reversed to face in the opposite direction by rotating the supporting arms upon the standard.

The operation of the machine will be 25 clear to those skilled in the art, but may be briefly described as follows:

The suspension mechanism is to be so adjusted that when the iron is hanging freely, *i. e.*, not resting upon the buck, its lower 30 surface will be two or three inches below the working level, *i. e.*, the level at which the iron will rest upon the buck or press-board proper. In this freely suspended condition the iron is ordinarily near one end 35 or the other of the trolley bar, and the spring 9 at that end will be nearly or quite fully compressed. The spring 18 of the suspension rods will at that time be fully compressed, its coils in contact with each other 40 and the extension of the lapped suspension rods positively limited.

It will be understood that the details of construction may be varied without departing from my invention.

45 I claim—

1. In a pressing machine, a supporting standard, arms extending divergently therefrom, a trolley-track supported by said arms, a carriage on said track, suspension 50 mechanism supported by said carriage, and a pressing iron hung upon said suspension mechanism.

Copies of this patent may be obtained for five cents each, by addressing the "Commissioner of Patents, Washington, D. C."

2. In a pressing machine, the combination with a suitable overhead trolley frame and a trolley carriage movable thereon, of a 55 pressing iron suspension mechanism comprising a rod connected with said carriage, a rod connected with the pressing iron, the lower end of the upper rod lapping the upper end of the lower rod, a stop upon 60 one rod, another stop adjustably fixed upon the other rod, said rods being relatively slidable and parallel, and a compression spring interposed between said stops and tending to lift the iron. 65

3. In a pressing machine, the combination of a single standard, a head adjustable rotatably thereon, divergent arms carried by said head, depending track supporting links carried by said arms, coiled springs 70 on said links, a trolley track yieldingly carried by said coiled springs, a carriage mounted on said trolley track, and a pressing iron resiliently suspended from said carriage. 75

4. In a pressing machine, the combination with a suitable overhead supporting frame, of a pressing iron suspension mechanism comprising an upper link rod flexibly connected with said overhead support, a lower 80 link rod carrying at its lower end a pressing iron, a guide-block fixed upon the lower end of the upper link-rod, through which the upper part of the lower link rod extends, an adjustable stop-block embracing the overlapping parts of both link-rods, a locking device for fixing said stop-block in adjusted position, and a coiled expansion spring interposed between said adjustable stop-block and the guide-block and tending to lift said 85 iron, but fully compressible thereby. 90

5. In a pressing machine, the combination with an overhead supporting frame and a pressing iron suspension mechanism connected therewith, of an adjustable clamp carried 95 by said suspension mechanism, comprising a body bar, a jaw mounted on each end of said bar and guided to move longitudinally of the latter, means for fixing each of said jaws in adjusted position, and an attachment device arranged mid-length of said bar. 100

CARL E. CAPMAN.
